UNITED STATES PATENT OFFICE.

HAROLD V. McCORMICK, OF LONG BEACH, NEW YORK, ASSIGNOR TO SHUR LOC ELEVATOR SAFETY CO. INC., OF NEW YORK, N. Y., A CORPORATION OF NEW YORK.

ELEVATOR.

Application filed January 24, 1927. Serial No. 163,032.

This invention relates to devices for controlling the movement of elevator cars and to devices for effecting and controlling the movement of elevator doors. One object of the invention is to provide improved means whereby the opening of the elevator door shall be prevented until the car has been brought substantially to rest, whether the car be moving under power or by its own momentum. Another object of the invention is to provide improved means whereby the positioning of the car substantially at the floor level must be accomplished before the door can be opened. Still another object is to provide improved means for effecting the movement of the door whereby the speed of movement of the door shall be controlled and the momentum of the door in approaching either extreme position shall be overcome in such manner as to prevent shocks, regardless of the weight of the door. Also in accordance with the invention provision is made whereby engagement between the door and its operating means is effected through the initial movement of such means.

The invention will be more fully explained hereinafter with reference to the accompanying drawings in which it is illustrated and in which:

30 Figure 1 is a view in elevation, partly diagrammatic, showing so much of an elevator and its appurtenances as is necessary to enable the application of the invention to be understood.

35 Figure 2 is a view partly in elevation and partly diagrammatic, illustrating the electro-magnetic devices and the electrical connections thereof for controlling the movements of the car and of the door and the mechanical devices through which the movement of the door is controlled.

40 Figure 2^a is an enlarged detail view of a portion of the mechanical devices shown in Figure 2.

45 Figure 3 is a detail view in sectional elevation illustrating particularly the devices for effecting and controlling the movement of the door.

50 Figures 4 and 5 are detail views in elevation illustrating in different positions the connections between the door and its actuating device.

55 In the embodiment of the invention illustrated in the drawings, an elevator car *a* is arranged to be moved in an elevator shaft *b* by

any usual or suitable hoisting mechanism sufficiently indicated by the cable *c*, a winding drum *c'*, which may be located on the floor of the pent house, and a motor indicated at *c*² in Figure 2. The power to move the door, which in this instance is the shaft door, is shown as supplied by a motor driven air compressor *d*, which is connected through an equalizing tank *d'*, a pipe *d*² and a slack hose *d*³ with a valve *d*⁴ on the car through which air under pressure is admitted to the door motor, hereinafter described, to move the door in one direction or the other. The valve *d*⁴ is controlled by means to be described hereinafter. Current to actuate the motor *c*² may be supplied from any suitable source through feed wires *e*, *f*, and the main elevator control panel, indicated at *g* in Figure 1, while its arrangement is shown in detail in Figure 2, connection being made through a cable *g'* with the controller *g*² on the car and through the cable *g*³ with an electro-magnetic device *g*⁴ on the car for operating the valve *d*⁴, this device being shown in the present instance as a stalled motor, to be more particularly referred to 80 hereinafter. Connection is also made from the control panel, as at *g*⁵, with a circuit controlling magnet *g*⁶, which may be located at any convenient point, preferably in proximity to the control panel in the pent house. 85

The door controlling valve *d*⁴ is shown as a four-way valve, having a connection for the feed pipe *d*³, an exhaust port and connections for pipes *d*⁵, *d*⁶, to opposite ends of a power cylinder *h* mounted on the car. The piston *h*' is fixed on a rod *h*² which carries a rack *h*³ in engagement with a segment *h*⁴. The latter is fixed on the axis *h*⁵ of a toggle lever *h*⁶. The coacting toggle lever *h*⁷ is connected with a slide *h*⁸ mounted to reciprocate on rails *h*⁹ on the car. The slide *h*⁸ carries two inter-connected and coacting arms *h*¹⁰ which, normally in inactive or retracted position, as shown in Figure 5, may be swung to extended position, as shown in Figure 4, to engage between them 100 a bar *i* secured to the shaft door *z*'. The arms *h*¹⁰ are held normally in inactive or retracted position by a spring *h*¹¹ which may be applied to one of them and are swung to extended position in the initial movement of the slide *h*⁸ by the coaction of a roller carrying arm *h*¹² on one of the arms or jaws *h*¹⁰ and a fixed bar *h*¹³. When the slide *h*⁸ is in the extreme position which corresponds to the closed position of the door, the roller of the arm *h*¹² is slight-

105

110

ly beyond the end of the bar h^{13} , as shown in Figure 5, but as soon as the movement of the slide begins the roller of the arm h^{12} is drawn upon the bar h^{13} and the jaws h^{10} are moved from the retracted position shown in Figure 5 to the extended or active position shown in Figure 4, grasping the bar i between them.

In the fully closed position of the door i it is locked in closed position by a latch i^2 , which engages a toothed rack i^3 secured to the frame of the shaft. The latch i^2 forms one member of a spring pressed bell crank i^2, i^4 , the other member i^4 of which is acted upon in the closing movement of the jaws h^{10} to disengage the latch i^2 from the toothed rack i^3 . It will be seen, therefore, that until the movement of the door opening device is initiated the door itself is held locked against movement.

Provision is made for controlling the movement of the slide h^8 and therefore of the door with it so as to prevent shocks when the door reaches the limit of its movement in either direction, regardless of the weight of the door. To accomplish this purpose there is associated with the door moving means a retardation device, such as that illustrated particularly in Figure 3. As there shown, the piston rod h^2 carries a piston h^{14} arranged to reciprocate in a cylinder k which has associated therewith a reservoir k' for oil or other suitable liquid. For convenience in construction, the cylinder k is provided with a liner k^2 which has near each end a large inlet port k^3 for communication with the reservoir k' , and adjacent the inlet port k^3 a longitudinal series of outlet ports k^4 . The wall of the cylinder k carries a spring closed inlet valve k^6 for each inlet port k^3 and may be formed with a large outlet port k^7 for each series or group of outlet ports k^4 in the liner k^2 . The ports k^4 are so designed as to size as to provide in the aggregate a substantially free outlet for the oil from the corresponding end of the cylinder k to the reservoir and therefore create but little resistance to the movement of the piston h^{14} and, through its connection with the piston h' , of the latter also and of the door which, through the operating devices, moves with it. Throughout the greater part of its movement the door is therefore moved rapidly, but as it approaches the limit of its movement in either direction the piston h^{14} overlaps in succession the ports k^4 of the corresponding group and successively closes them against the outlet of the oil, increasing the resistance until all of the outlet ports of that group are closed and the piston h^{14} and the parts connected with it are brought to rest. The inlet valve at the other end of the cylinder k , opening inward from the reservoir k' to the interior of the cylinder k , permits free movement of the oil into the cylinder behind the piston.

The movable member d^7 of the four-way

valve d^4 is so controlled in its movement that motive power cannot be applied for the opening of the elevator door unless the car is substantially at the level of a floor. There is therefore placed at each floor lever a cam-shaped resistance device l , the resistance of which permits such movement of the movable valve member d^7 as is necessary to effect opening movement of the door. If the car is not approximately at the floor level, so as to permit coaction of the resistance device l with an element carried by the car, the movable valve member d^7 cannot have such movement and the door therefore will not be opened except by the operation of some emergency device.

In the embodiment of the invention illustrated, an arm d^8 of the movable valve member d^7 is connected by a link l' with an arm l^2 of a weighted segment l^3 which is held normally in elevated position by the electro-motive device or stalled motor g^4 , previously mentioned, so long as such electro-motive device is energized. It is also retained in its elevated position by a bell crank latch l^4 pivoted on another arm l^5 of the weighted segment l^3 , the latch normally engaging a fixed detent l^6 to hold the segment in elevated position. The other arm of the bell crank latch l^4 is connected, as by a link l^7 , with a roller-carrying arm l^8 mounted on the car in position to coact with the cam-shaped stop or resistance device or element l at the floor level at which the car is to be stopped. When the car is stopped at a floor level or otherwise, the electro-motive device g^4 is de-energized and the weighted segment l^3 is free to act to shift the movable valve member d^7 if not prevented by the latch l^4 . If the car is stopped at a floor level, so that the roller-carrying arm l^8 may coact with the resistance element l , the initial movement of the segment l^3 by reason of the resistance offered by the resistance device l , the arm l^8 , the link l^7 and the shorter arm of the bell crank latch l^4 , causes the bell crank latch to be disengaged from the detent l^6 so as to permit continued, effective movement of the weighted segment l^3 . If, however, the car is not at a floor level and no resistance is offered to the movement of the roller-carrying arm l^8 , the latch l^4 will not be disengaged from the detent l^6 and effective movement of the weighted segment l^3 cannot take place.

The electrical devices and connections by which the movements of the car and of the door are controlled are illustrated in Figure 2. For the most part, except as hereinafter indicated, they are arranged and function substantially in the same manner as electrical controlling devices heretofore employed. One of the feed wires, as f , is connected through conductors f' , f^2 of the cable g' and the usual interlock switch f^3 with the terminals f^4 , f^5 arranged to be connected through

the controller f^6 with the terminals f^7 , f^8 respectively, the latter being connected through conductors f^9 , f^{10} with the other feed wire e through the respective magnets f^{11} , f^{12} .
 5 Through the switches m , n and m' , n' , operated in pairs by the magnets f^{11} and f^{12} respectively current is supplied to the armature of the elevator motor c^2 in one direction or the other, through the conductors m^2 , n^2 and the brushes m^3 , n^3 of the motor, to drive the hoisting drum in one direction or the other. The field coils of the motor c^2 are energized from the feed wires e , f , through direct connections e' , e^2 . It will be observed
 10 that conductors m^4 and n^4 supply current from conductors m^2 and n^2 to the coils of the relay magnet g^6 , the coils of this magnet being connected in parallel with the coils of the armature of the elevator motor c^2 . Accordingly, so long as the armature of the direct current motor c^2 is rotating above a certain predetermined minimum speed the coils of the magnet g^6 will continue to be energized, notwithstanding the opening by the
 15 switches m' , n' of the connection to the feed wires e , f , and through such energization of the magnet g^6 its armature g^7 will continue to be held toward the magnet so as to close at the terminals o , o' the circuit from the
 20 main feed wires by the branches e^3 , e^4 and the conductor e^5 through the coils of the door controlling electro-motive device g^4 . It will be noted that a push button switch e^6 will be inserted between the branches e^3 and e^5 to close
 25 the circuit to the coils of the electro-motive device g^4 for the purpose of effecting closure of the door.
 So long, therefore, as power is supplied to the elevator motor c^2 , it will be supplied also
 30 to the electro-motive device g^4 and the weighted segment will be held in its elevated position and the valve d^4 held in such position as to cut off the supply of motive fluid to the door operating motor h . The door, therefore, cannot be opened automatically so long as power is supplied to the elevator motor. When, however, the car is to be stopped at a floor which it is approaching, the power will ordinarily be cut off before the car reaches
 35 the floor and power might therefore be supplied to the door opening mechanism before the car reaches the floor at which it is to stop. To prevent this action advantage is taken of the action of the armature of the direct current motor c^2 while it is slowing down and before it ceases altogether to rotate, to continue the energization of the magnet g^6 and therefore, as described above, the energization of the electro-motive device g^4 , thereby
 40 to maintain the controlling valve d^4 in position to prevent the application of power to the door operating motor. When, however, the armature of the elevator motor c^2 has slowed down to a predetermined degree, it
 45 will cease to energize the magnet g^6 suf-

ficiently to hold its armature and the circuit through the door controlling electro-motive device g^4 will therefore be opened and the weighted segment l^3 will be permitted to act to shift the valve d^4 so as to supply power to the door operating motor h , provided also the car is positioned approximately at the level of the floor so that the latch l^4 shall have released the weighted segment as already described.

It will be understood that various changes in details of construction and arrangement can be made to suit different conditions of use and that, except as pointed out in the accompanying claims, the invention is not restricted to the particular construction and arrangement shown and described herein.

I claim as my invention:

1. The combination of a door having an arm, a slide, means to support the slide for reciprocating movement, operating devices for the slide, a spring pressed arm pivoted on the slide adapted to engage the arm on the door and having a secondary arm extended therefrom, and a fixed bar with which said secondary arm is engaged in the initial movement of the slide to cause the door engaging arm to move into operative position.

2. The combination of a door, a door operating motor in operative relation with the door, a source of power connected to the motor, a device to control the supply of power to the door operating motor, means to operate said device, means to prevent operation of said device, and means to release said preventive means.

3. The combination of a door, a door operating motor in operative relation with the door, a source of power connected to the motor, a device to control the supply of power to the door operating motor, a weighted means connected to said device to operate the same, means to prevent operation of said weighted means, and means to release said preventive means.

4. The combination of a door, a door operating motor in operative relation with the door, a source of power connected to the motor, a device to control the supply of power to the door operating motor, a three armed lever having one arm weighted, an operating connection from another of the arms of the lever to said device, a latch pivotally mounted on the third arm of the lever, a detent to be engaged by the latch, and means to release the latch.

5. The combination of a door, a door operating motor in operative relation with the door, a source of power connected to the motor, a device to control the supply of power to the door operating motor, a three armed lever having one arm weighted, an operating connection from another of the arms of the lever to said device, a bell crank latch pivotally mounted on the third arm of the lever,

a detent to be engaged by the latch, an arm operatively connected with the bell crank latch, and means to offer resistance to the movement of said arm, whereby in the initial 5 movement of the three armed lever the latch is released and full movement of the three armed lever is permitted.

6. In an elevator, the combination of a 10 car, means to operate the car, a door, door operating devices, means mounted on the car to determine the operation of said devices, means acting normally when the car comes to rest to prevent operation of such determining means, and means located at each floor to 15 permit the operation of such determining means only when the car is at a floor level.

7. In an elevator, the combination of a 20 car, means to operate the car, a door, door operating devices, means on the car to control the operation of said door operating devices, means on the car to prevent operation of said devices, and means at each floor to release said preventive means.

8. In an elevator, the combination of a 25 car, means to operate the car, a door, door operating devices, means on the car to determine the operation of said door operating devices, means on the car to prevent operation of said controlling means, and means at each floor to 30 release said preventive means.

9. In an elevator, the combination of a 35 car, means to operate the car, a door, door operating devices, means on the car to control the operation of said door operating devices, a weighted means on the car to operate said controlling means, a latch to prevent operation of said last named means, and means at each floor to effect release of said latch.

10. In an elevator, the combination of a 40

car, means to operate the car, a door, door operating devices, means on the car to control the operation of said door operating devices, a three armed lever mounted on the car, one arm being weighted, an operative 45 connection from another arm to said controlling means, a latch pivoted on the third arm, a detent to be engaged by said latch to prevent movement of the three armed lever, an arm pivoted on the car and operatively connected with said latch, and a resistance device at each floor level for cooperation with said arm whereby in the initial movement of the three armed lever the latch is released to permit full movement of the three armed lever. 50

11. In an elevator, the combination of a 55 car, a door, door operating devices, means to hold the door operating devices out of operation, a main elevator motor, means to cut off the supply of power to the motor, and means operative with the movement of the car after power has been cut off from the motor to prevent release of the door operating devices until the car comes substantially to rest.

12. In an elevator, the combination of a 60 car, a door, door operating devices, an electro-motive device to hold the door operating devices out of operation, a main elevator motor, means to cut off the supply of power to the motor, an electro-magnetic device energized by the movement of the motor after power has been cut off and connections controlled by said electro-magnetic device to 65 continue the supply of current to said electro-motive means to prevent the release of the door operating devices until the motor comes substantially to rest.

This specification signed this 11th day of January, A. D. 1927.

HAROLD V. McCORMICK.
